UNITED STATES PATENT OFFICE.

LOUIS DUFAY, OF VERSAILLES, FRANCE.

PROCESS FOR PHOTOGRAPHIC PRINTING IN COLORS.

Application filed January 25, 1924. Serial No. 688,568.

This invention relates to a process of preparing photographic proofs in colors, on paper or on all pervious supports, without the necessity of having recourse to the ordinary photographic manipulations which necessitate the use of various chemical reagents.

- This process is essentially characterized in that one or more photographic proofs 10 printed with fat ink (hereinafter described), for instance, on paper or other suitable support, are colored either by projection of a color powder, capable of being retained by the ink, or by direct introduction of the 15 color in the latter; the pervious papers or supports adapted to receive the impression are then directly applied and in a moist condition, on the proof or proofs coated with coloring material.
- 20 The proof or proofs will therefore be capable of being reproduced in several similar copies; the number of copies varying with the dyeing power of the coloring matters used.
- 25 In the accompanying drawing and by way of example:

Fig. 1 illustrates the image in colors it is desired to reproduce in several copies, the conventional hatchings indicating the color 30 of the various portions of the image.

Figs. 2, 3 and 4 illustrate the colored prints of the photographic proofs of the image obtained by the trichrome method; these proofs have been taken through colored selecting screens, for instance, so that 35 the proof (Fig. 2) may reproduce only the red portions of the original proof, the proof (Fig. 3) the blue portions and the proof (Fig. 4) the yellow portions.

40 Figs. 5, 6, 7 show the reproduction of the colors obtained by applying the paper or the pervious support, previously moistened, successively on each of the proofs, Figs. 2, 3, 4.

The process, forming the subject-matter 45 of the invention, essentially consists in printing, with a suitable ink, a fat ink for instance, by any printing process, a photographic proof. If to the ink is added an agglutinative or sticky material (fatty varnish, gum or the like), this ink will be able 50 to retain any pulverulent material driven on the surface of the proof, before drying. If this pulverulent material is colored, the proof will therefore give, by contact, several 55 reproductions, the number of which will vary with the dyeing power of the coloring

matter used as a powdering. For that purpose, it is sufficient to slightly moisten the paper or pervious support adapted to receive the printing and to apply it, in a moist condition, directly on the proof coated with coloring matter.

It will be possible, as shown in the accompanying drawing, in order to obtain poly-chromatic reproductions, to successively apply the paper or pervious support on a series of proofs, obtained from the same image, but the portions of which are differently colored. It will thus be possible by starting from prints of selected proofs of 70 the same image, to obtain trichrome reproductions which will all be exactly identical.

As illustrated in the drawing, it will be supposed that it is desired, starting from a color subject (Fig. 1) composed of blue, red, 75 yellow, green and violet, to obtain identical reproductions, on paper for instance.

Three negatives are taken from the subject or image by means of colored selecting screens, for instance; and there is obtained 80 for example:

1°—A negative containing the red shades and the red shades of the violet colors.

2°—A negative containing the blue shades and the blue shades of the green and violet 85 colors (Fig. 3).

3°—A negative containing the yellow shades of the green colors.

These negatives will give three proofs 90 printed with fatty ink and which are powdered as follows:

Proof No. 1—with a red color,

Proof No. 2—with a blue color,

Proof No. 3—with a yellow color, which will give the representations of Figs. 2, 3, 4. 95

The paper or pervious support, previously moistened, will then be applied on the proof No. 1 (Fig. 2) which will permit the reproduction of the red colors of the subject. The impression received by the pervious support 100 is shown in Fig. 5.

This support, after suitable registering, will be applied on the proof No. 2 (Fig. 5) which will permit the reproduction of the violet and blue shades (blue and red). The 105 impression received by the pervious support is shown in Fig. 6.

The same support will then be applied on the proof No. 3 (Fig. 4) which will permit the reproduction of the yellow and green 110 shades (blue and yellow). The final printing of the support is shown in Fig. 6 and

reproduces the colors of the original subject or image.

The same series of operations effected on other papers or previous supports will therefore give as many reproductions of the subject or image as the dyeing power of the coloring matters used will allow.

Instead of powdering the proofs with a coloring powder as indicated, this operation can be avoided by directly adding the coloring matter to the ink which can be of any nature whatever and by incorporating it therewith by grinding.

Methylene blue, fuchsin, methyl violet, tartrazine, which are capable of a perfect porphyrization and which have a considerable dyeing power, give excellent results for the application of the present process. They give combinations of colors of a great variety, a good trichrome synthesis and printings which can reach several hundreds of copies.

What I claim as my invention and desire to secure by Letters Patent is:

A process for color printing comprising the following steps, producing a plurality of color-separation negatives from a colored original, making a similar number of printing plates from these color-separation negatives, printing said printing plates with a fatty ink on a single support, powdering the printed impression after each impression with a water-soluble dye, said dye corresponding in color to the color filter used in making the printing plate, moistening a sheet of material adapted to receive a colored impression, pressing the material against the composite powdered impression whereby a transferred impression is obtained on the material reproducing the colored original.

In testimony whereof I have signed my name to this specification.

LOUIS DUFAY.
